SUSPENDER BACK COUPLING

Jacob S. Hawie, Bridgeport, Conn., assignor to
The Hawie Manufacturing Company, Bridge-
port, Conn.

Application March 7, 1946, Serial No. 652,681

6 Claims. (Cl. 24—83)

1

This invention relates to improvements in suspenders and more particularly to novel means for connecting the shoulder straps at the rear of suspenders.

Heretofore it was customary to connect the back straps by stitching them in crossed condition. Subsequently, metal members were used to allow the straps to occupy substantially vertical positions, and later the metal members were pivotally connected by a rivet or the like to allow one strap to move relatively to the other, following movements of the human body.

The primary object of the present invention is to provide a back strap coupling comprising a plurality of members, one or both of which may be threaded relatively to the other to provide a pivotal connection between the members without the employment of tools for pivotally connecting the members.

Another object of the invention is to supply a pivotal back strap coupling adapted to be formed of sheet metal or plastic and which may be readily assembled by hand.

With the foregoing objects outlined and with other objects in view which will appear as the description proceeds, the invention consists in the novel features hereinafter described in detail, illustrated in the accompanying drawing, and more particularly pointed out in the appended claims:

In the drawing:

Fig. 1 is an elevation of one embodiment of the invention shown applied to suspender straps, illustrated in dot-and-dash lines.

Fig. 2 is an enlarged view of the back strap coupling with one member arranged at an angle to the other and shown in dot-and-dash lines.

Fig. 3 is a top plan view of the structure shown in Fig. 2.

Fig. 4 is an elevation of a modification.

Fig. 5 is a top plan view of the structure shown in Fig. 4.

Fig. 6 is an elevation of a still further modification.

Referring to Figs. 1 to 3, inclusive, 1 and 8 designates suspender straps connected at the rear of the suspenders by a back coupling 9. In this embodiment of the invention, the coupling is formed of a pair of identical slender sheet metal members, each consisting of a tapered end portion 10, a loop end portion 11, and a neck 12. The tapered part is preferably of wedge-shaped and provided with a pair of substantially parallel slots 13, for the reception of a strap of the suspenders.

The loop of one of the members includes a 55

2

curved or arcuate shaped inner edge portion adjacent the neck 12 with the ends of the arcuate parts connected by a bar 14. The other member of the coupling is also provided with a curved or arcuate or inner edge portion adjacent the neck 12 with the ends of the arcuate arms connected by a bar 15. The loops are distorted as indicated at 16 in Fig. 3, so as to permit the bars 14 and 15 to be arranged in offset parallel relationship.

In assembling the members of this type of connection, the tapered portions of the two bodkin-like members are interthreaded through the loop portions 11 of one another, so as to place the bar 15 of one member at one side of the coupling and in sliding contact with the neck 12 of the other member, and the bar 14 of the latter at the opposite side of the coupling and in slidably engagement with the neck 12 of the first member, as will be evident from the drawing. This will provide a pivotal connection between the two members whereby either may turn relatively to the other, as is clear from the dotted-and-dash line showing in Fig. 2.

The modification shown in Figs. 4 and 5 is similar to that in Figs. 1 to 3, inclusive, except that the loop 17 of each is substantially circular instead of provided with one straight side bar.

In the form of the invention illustrated in Fig. 6, the members are not identical. One of them, 18, may be exactly like any one of the members shown in Figs. 1 to 5, inclusive, but the other member 19, instead of being provided with a loop, terminates in a disk 20. In this form of the invention, of course, only one member is threaded through the loop of the other.

From the foregoing, it is believed the construction, use and advantages of the invention may be readily understood, and I am aware that changes may be made in the details disclosed without departing from the spirit of the invention, as expressed in the following claims:

What I claim and desire to secure by Letters Patent is:

1. A back coupling for suspenders or the like, comprising first and second substantially rigid elongated members, each having a bodkin-like element at one end portion provided with substantially parallel strap-receiving slots extending lengthwise of the member, the opposite end portion of at least one of the members being provided with a loop through which the other member is threaded for pivotally connecting the members, the loop having a curved inner edge portion to facilitate turning one member relatively to the other.

2. A back coupling for suspenders or the like, comprising first and second substantially rigid elongated members, each having a bodkin-like portion at one end and a loop at its opposite end, each of the bodkin-like portions being provided with substantially parallel strap-receiving slots extending lengthwise of the member, said members being interthreaded through their loop portions so that the loop of the first member slidably engages one side of the second member and the loop of the second member slidably engages the opposite side of the first member, the loop of each member having a curved inner edge portion to facilitate turning of each member relatively to the other member.

3. A back coupling for suspenders or the like, comprising first and second substantially flat overlapping elongated members arranged in substantially the same plane, each member being provided at one end with strap-receiving slots and at its opposite end with a loop, said slots extending lengthwise of each member said members being interthreaded through their loop portions so that the loop of the first member slidably engages one side of the second member and the loop of the second member slidably engages the opposite side of the first member, the loop of each member having a curved inner edge portion to facilitate turning of each member relatively to the other member.

4. A back coupling for suspenders or the like, comprising first and second substantially rigid elongated members, each consisting of a bodkin-like element having a loop at one end, a neck and strap-receiving slots between the neck and its opposite extremity, the slots of each member being substantially parallel and extending lengthwise of the member, said members being interthreaded through their loop portions so that the loop of the first member slidably engages one side of the neck of the second member, and the loop of the second member slidably engages the opposite side of the neck of the first member, the loop of each member having a curved inner edge portion to facilitate turning of each member relatively to the other member.

5. A pivotal back coupling for suspenders or the like, comprising first and second substantially rigid elongated members, each consisting of a bodkin-like element having a loop at one end, a neck and strap-receiving slots between the neck and its opposite end, the slots of each member being substantially parallel and extending lengthwise of the member, said members being interthreaded through their loop portions so that one side of the loop of the first member slidably engages one side of the neck of the second member, and the opposite side of the loop of the second member slidably engages the opposite side of the neck of the first member, the loop of each member having a curved inner edge portion to facilitate turning of each member relatively to the other member.

10 6. A back coupling for suspenders or the like, comprising first and second substantially rigid bodkin-like members, each having one end portion provided with substantially parallel strap-receiving slots extending lengthwise thereof, the opposite end portion of one of the members being provided with a loop through which the other member is threaded for pivotally connecting the members, said loop having a curved inner edge portion to facilitate turning of one member relative to the other member, and said other member having a substantially disk-shaped end cooperating with said loop.
